DISPLAY PEDESTAL FOR FRUIT OR THE LIKE

Edward C. Bruno, 1880 S. Monaco,
Denver, Colo. 80222

Filed Jan. 24, 1966, Ser. No. 752

Term of patent 14 years

(Cl. D80—9)

FIGURE 4 is an elevational view taken from one end thereof, showing the pedestal in a display position different from that shown in FIGS. 1 through 3; and

The broken line representation of a piece of fruit in FIGS. 4 and 5 is for purposes of illustration only.

I claim:

The ornamental design for a display pedestal for fruit or the like, as shown and described.
